CONTAINER WITH RETAINING CAP

Harry B. Griner, Magnolia, N. J.

Application January 28, 1937, Serial No. 122,759

6 Claims. (Cl. 221—60)

The object of this invention is to devise a novel container and retaining cap which when assembled will provide an air tight seal and which can be manufactured at a lower cost and with less waste of material than the threaded or screw type caps which are now generally employed.

A further object of the invention is to construct the discharge end of the container and the cap in such a manner that the cap can be pressed into sealed and hinged relation with its container.

A further object of the invention is to construct the discharge end of the container with a self cleaning distributing nozzle.

A further object of the invention is to devise a novel hinge connection between the container and cap, and to provide a cooperating locking shoulder and groove on the container and cap so that the cap can be readily swung open, and, when closed, will provide a compression seal.

With the above and other objects in view as will hereinafter clearly appear, my invention comprehends a novel container and retaining cap.

It further comprehends a novel construction of the discharge end of a container, and a novel construction of a cap to cooperate with said discharge end.

Other novel features of construction and advantage will hereinafter clearly appear in the detailed description and the appended claims.

For the purpose of illustrating the invention, I have shown in the accompanying drawing typical embodiments of it, which, in practice, will give satisfactory and reliable results. It is, however, to be understood that the various instrumentalities of which my invention consists can be variously arranged and organized and my invention is not limited to the exact arrangement and organization of these instrumentalities as herein set forth.

Figure 1 is an elevation of an assembled container and cap embodying my invention.

Figure 2 is a sectional elevation of the cap, in detached position.

Figure 3 is a side elevation partly in section of the discharge end of the container.

Figure 4 is a side elevation partly in section of the container and its cap.

Figure 5 is a top plan view of the cap in detached position.

Figure 6 is a side elevation of the container and cap showing the cap in open position.

Figure 7 is a side elevation on an enlarged scale, showing more clearly the manner in which the cap is assembled with the container.

Figure 8 is a top plan view of the discharge end of the container with the cap removed.

Figure 9 is a sectional detail of another form of hinge which may be used.

Similar numerals of reference indicate corresponding parts.

Referring to the drawing:

A container 1 may be of any desired type but is preferably in the form of a collapsible tube for the reception of plastic material such as for example, tooth paste, medicinal preparations and the like.

The discharge end of the tube is of novel construction and terminates in a self-cleaning distributing nozzle 2, the outer wall of which flares rearwardly as at 3. As illustrated, the wall of the container converges outwardly as at 4 to merge into a cylindrical portion 5 which merges into the inwardly extending portion 6 which connects with the distributing nozzle 2.

The portion 5 has an external cylindrical shoulder or bead 7 which is semi-circular in cross section to form a locking flange. The outwardly converging portion 4 has a lug 8 having integral with it the trunnions or hinge members 9 which have a special contour. They are rounded at the bottom and the sides converge upwardly at the upper end, see more particularly Figure 7.

A retaining cap 10 is made in one piece and although it may be made of any suitable material, it is preferably made of bakelite. The retaining cap 10 has a rounded auxiliary sealing portion 11 surrounded by an annular recess 12. The inner face of its flange is provided with an annular recess or groove 13. The flange is split at its rear portion, as seen in Figure 2.

The cap has a bifurcated hinge block 14, the arms of which have a round opening 15 which at the bottom flares in opposite directions as at 16 to form a guide throat.

The cap has a lift nib 17.

In order to assemble the cap with the container, the cap is pressed towards the container. The trunnions 9 pass through the guide throat 16 and into the opening 15, the walls of which form a bearing. At the same time the sealing portion 11 enters the nozzle 2 and the end of the nozzle is compressed by the walls of the recess 12. The locking flange 7 snaps into the recess or groove 13, thus forming an efficient and positive lock which can be handled without leakage.

The arms of the hinge block 14 have sufficient spring for the trunnions to snap into place and

the cap is thus retained in hinged connection with the container.

The cap can be easily and quickly opened and closed by the thumb of the hand which grasps the container.

In the preferred construction herein disclosed, I do not employ threads, springs or pins, and, as only two parts are employed, the container and retaining cap can be very economically 10 manufactured.

In the embodiment seen in Figure 9, I have shown a different form of a hinge, in which the pin passes through an opening in the lug 8 and the arms of the hinge block 14.

15 It will be noted that the nozzle extends beyond the end of the container and terminates in an annular edge. If the container 1 is for tooth paste, and the tooth brush is drawn across the nozzle, a slight vacuum is created within the nozzle which causes the tooth paste to be withdrawn within the nozzle.

It will now be apparent that I have devised a new and useful container with retaining cap which embodies the features of advantage enumerated as desirable in the statement of the invention and the above description, and while I have, in the present instance, shown and described preferred embodiments thereof, which will give in practice satisfactory and reliable results, it is to be understood that these embodiments are susceptible to modification in various particulars without departing from the spirit or scope of the invention or sacrificing any of its advantages.

35 Having thus described my invention, what I claim as new and desire to secure by Letters Patent is:—

1. A container having a discharge nozzle and a lug, a cap having a split flange and arms, said 40 arms pivotally connected to said lug, said cap having a rounded sealing portion adapted to enter into said nozzle, and said container and cap having cooperating locking means to lock the cap to the container in a sealed condition.

45 2. A collapsible container having a discharge nozzle and a lug having trunnions, a cap having a hinge member, a plurality of walls defining said hinge member, each of said walls having an aperture therein whereby when said cap and container are moved upon each other the trunnions 50 will snap into said apertures and retain the cap and container in hinged relationship.

3. A collapsible container having a discharge nozzle and a lug provided with trunnions, a cap having a rounded sealing portion adapted to enter said nozzle, the sealing portion in said cap having a groove therein whereby said groove and 5 the edge of the nozzle will interfit, said cap having arms, each arm having an aperture therein which opens through its bottom, each aperture adapted to receive one of said trunnions whereby the cap is hingedly mounted, and said container 10 and cap having cooperating locking surfaces.

4. A collapsible container having a discharge nozzle and a lug provided with trunnions, a cap having a rounded sealing portion to enter said nozzle, a groove around the sealing portion of 15 said cap whereby said groove interfits with the edge of the nozzle, said cap having a bifurcated hinge portion defined by spaced arms, each arm having an aperture which opens through its bottom to receive one of said trunnions, and said 20 container and cap having cooperating sealing surfaces.

5. A collapsible container having a projecting nozzle at its discharge end, a lug having trunnions, a locking portion on said nozzle, a cap 25 having arms, said arms defining a slot which flares downwardly towards its bottom, said slot and said lug interfitting, each arm having an aperture therein whereby the complementary trunnions will snap into the apertures when the 30 cap and container are pressed together, said cap having a split flange, and a depression on the inner face of said flange to receive the locking portion of said container to retain the cap in sealed condition with the container.

35 6. A collapsible reservoir having a projecting nozzle, a discharge passageway in said nozzle, a bead on the outside of said nozzle, a lug mounted on said reservoir adjacent said nozzle, a pair of trunnions mounted on said lug, a cap having a 40 pair of spaced arms, each of said arms having an opening therein which interfits with one of said trunnions whereby the cap is pivotally mounted, a projecting member on said cap adapted to tightly interfit with the inside of said discharge 45 passageway whereby the passageway will be sealed from the atmosphere when the cap is in closed position, and a flange on said cap adapted to tightly interfit with said bead.

HARRY B. GRINER.
